UNITED STATES PATENT OFFICE.

FRANCIS M. VANDERVOORT, OF PUEBLO, COLORADO, ASSIGNOR TO THE POSITIVE LOCK COMPANY, OF PUEBLO, COLORADO, A CORPORATION OF COLORADO.

LATCH.

Application filed September 13, 1923. Serial No. 662,466.

This invention relates to latches; particularly to latches adapted for use on automobiles or other vehicles. Although latches embodying the invention take account of 5 and meet the exacting requirements of service peculiar to latches used on automobiles and although, for purposes of illustration, a latch embodying the invention is shown and described as used on an automobile, it 10 is to be clearly understood that such use is only one of many uses to which latches embodying the invention may be put. It is also to be understood that the term latch used throughout the specification and claims 15 includes both latch and lock constructions.

An object of this invention is to provide a latch of simple construction which will permit the door or other closure member to which the latch is attached to be easily 20 closed, the latch firmly holding the closure member in closed or latched position without substantially any rattling of the closure member or of the latch parts.

It is also an object of the invention to 25 provide a latch which will not only prevent substantially all rattling of the latch parts and closure member when the parts are new and carefully fitted, but also to prevent substantially all rattling of these parts even 30 if they are poorly fitted or worn and strained from long usage.

Other objects and features of construction will be apparent from the following description taken in connection with the accompanying drawings which illustrate a typical construction embodying the principles of the invention. In these drawings,

Fig. 1 is a side elevational view of a latch and cooperating keeper embodying the invention, shown in the position the parts occupy when mounted on the door and door jamb, respectively, of an automobile, parts of the door and door jamb being indicated by dotted lines;

Fig. 2 is an end view of the latch and its cooperating keeper, looking to the right of Fig. 1;

Fig. 3 is a sectional view taken on the line 3-3 of Fig. 1 looking in the direction of the arrows;

Fig. 4 is an end view of the latch only, and

Fig. 5 is a plan view of the keeper only.

Broadly stated, the invention comprises

a mounting or casing, abutment means pro-

jecting therefrom, and latching means movable longitudinally and laterally with respect to said abutment means.

Stated more specifically, the invention comprises a casing or mounting, an abutment member, provided with an inclined portion, projecting from said casing or mounting, and a latch member adapted to be longitudinally projected and retracted, said latch member provided with an inclined portion adapted to engage the inclined portion of said abutment member when the latch member is projected to spread said members apart and wedge them against substantially all lateral movement in a cooperating keeper.

Referring to the drawings, 10 indicates generally the latch mounting or casing which may be of any suitable or desired shape to support the parts of the latch. In the example illustrated, mounting 10 comprises a base plate 11 provided with apertures 12 to receive screws or other suitable fastening devices for securing the latch casing to the door, indicated in dotted lines at D. Plate 11 is provided at one end with an integral angular extension 13 forming the front face of the latch casing or mounting and arranged to lie flush with the free edge of the door. The extension or front plate 13 is provided with an aperture 14 to afford a passage for the latching means B therethrough. A housing plate 15 is secured to the base plate 11 by any suitable means to form therewith a housing or chamber for supporting and guiding the latching means and its associated mechanism.

The bolt B is supported for longitudinal and lateral movement by the casing indicated generally by 10. Bolt B may be of any suitable or desired construction, but the construction illustrated is preferred because of its lightness, comparative strength, and because such a construction can be easily and cheaply made of stamped sheet metal. As illustrated, the bolt B is U or channel-shaped, having a web portion 16 and depending flanges 17 and 18. The bolt is supported for sliding movement in the latch casing, one end passing through aperture 14 in the front plate 13 and normally projecting from the front plate or front end of the latch. The front or projecting end of the bolt is rounded at 19 and is adapted to strike a keeper plate indicated generally by 110

20 mounted in the edge of the door jamb, indicated in dotted lines by J, when the door is swung to close it, and thus slide the bolt into the casing against the tension of spring 5 21 which normally projects the bolt from the casing.

Associated with the bolt B and cooperating therewith to hold the bolt against substantially all lateral movement when the bolt is projected is an abutment means or plate 22. This abutment plate or bar 22 is supported in the latch casing against longitudinal movement. One end of the abutment 10 22 passes through aperture 14 in front plate 13 and permanently projects from the front face or end of the latch casing. Although the abutment means may take any suitable or desired form, the form illustrated is preferred. Abutment means 22 comprises a bar 15 or plate of substantially the same width as the distance between the sides or flanges 17 and 18 of the bolt B, the abutment means being mounted between said flanges or sides. The projecting or outer end 23 of abutment 20 means 22 is slightly reduced in width for a purpose to be explained hereafter. The rear or inner end of the abutment means 22 is bent to provide a substantially right angular extension or lug 24 which engages the rear or 25 inner end of the housing plate 15 and is held in engagement therewith by a tongue or lug 25 bent or struck out from base plate 11. The abutment member or plate 22 has a slot or recess 26 extending longitudinally 30 thereof. One end of the slot or recess 26 terminates adjacent the lug 24 of the abutment means and the other or outer end of the slot or recess terminates in an angular tongue or inclined portion 27 formed integral with the 35 abutment means. Slot or recess 26 forms a guide or support for spring 21, one end of the spring engaging the lug 24 of the abutment means and the other end of the spring engaging an integral tongue or lug 28 projecting from the bolt B, tongue or lug 28 40 projecting into the slot or recess 26.

The bolt B is provided with means adapted to co-operate with means carried by the abutment means to hold the bolt, abutment 45 means and operating means of the latch against rattling when the bolt is projected. Bolt B is provided with an inclined or beveled portion 29 which is adapted to engage the correspondingly inclined or beveled portion 27 of the abutment means when the bolt is projected to move both the bolt and the abutment means laterally and thereby clamp these members against lateral movement both in the latch casing and in the keeper means. 50 The web portion 16 of the bolt B is provided intermediate the ends of the bolt and adjacent the lug 28 with projections or pressed-out portions 30 which act as a fulcrum or bearings so that when inclined portion 29 of 55 the bolt engages inclined portion 27 of the

abutment means the projecting ends of the bolt and abutment means will swing away from each other with the projections 30 as pivot points.

The abutment means cooperates with the latching means to engage within and wedge in the keeper means so that relative lateral movement of these parts is prevented. Keeper 60 20 comprises a flat plate provided with holes 200 to receive screws or other fastening means for securing the plate to the door jamb J. Plate 20 has a beveled or cam portion 31 to cooperate with the rounded end 19 of the bolt and assist in sliding the bolt into the casing when the bolt strikes the keeper as the door is moved to closed position. Keeper plate 20 is also provided with a recess 32 to receive bolt B, the recess being generally U or trough-shaped to conform substantially to the contour of the bolt B. Leading from the beveled edge of the keeper plate and connecting with recess 32 is an opening or passage 33 just wide enough to allow passage of the reduced end 23 of the abutment means, but too small to allow passage of the bolt. When the door is swung to close it, the rounded end 19 of the bolt B, which projects from the free edge of the door, strikes the beveled portion 31 of the keeper plate and is thereby slid or pushed into the latch casing against the tension of spring 21 tending to project the bolt. The permanently projecting abutment means passes through the opening or passage 33 and enters the recess or opening 32 in the keeper and strikes against or engages the edge 34 of the recess 32. At or shortly before the time abutment 22 engages edge 34 the retracted bolt B had ridden over the surface of the keeper plate adjacent passage 105 33 and has entered the enlarged recess 32 formed to receive the bolt. As the bolt is projected into this recess by the action of spring 21, the beveled or inclined portion 29 strikes the correspondingly inclined or 110 beveled portion 27 of the abutment means to force the abutment means and latching means apart and into engagement with the edges of recess 32. As previously explained, recess 32 in the keeper plate 20 conforms generally to the contour of bolt B, so when the bolt engages in this recess the rounded corners 161 of the bolt are firmly clamped against the rounded edges 321 of the recess 32 to prevent substantially all lateral movement of the bolt in the striker plate 20. Lateral movement or separation of the latching and abutment means also forces these means into engagement with the casing to thus hold these means against rattling in the casing. 115 120 125

In order to release the bolt from engagement with the keeper means when it is desired to open the door, retracting means is provided. The retracting means in the present instance comprises a cam or roll 130

back 35 pivoted at 36 to back plate 11, the roll back being provided with cam portions 37 which engage in slots or notches 38 provided in the flanges or side portions 17 and 18 of bolt B. It will thus be seen that the roll back 35 is mounted between the flanges or sides of the bolt and as the roll back is turned by suitable handle means (not shown) engaging in the square aperture 39 of the roll back, the cam portions 37 will engage the bolt to retract the same. It will be observed as shown in Fig. 3 that when the bolt is wedged in the keeper recess, the bolt is not fully projected and that the lug 28 is slightly spaced from the roll back 35. When the bolt is not engaged in the keeper, roll back 35 acts as a stop to be engaged by lug 28 of the bolt and thus prevent the bolt from being pushed out of the casing too far. When the bolt is projected, the abutment means is forced by the bolt to engage the roll back and thus prevent rattling of the same.

It is to be understood that the invention is not limited to the exact arrangement illustrated and described and it will be obvious to those skilled in the art that various modifications in shape and arrangement of parts can be made without departing from the scope of the invention as defined in the appended claims.

What is claimed is:

1. A latch comprising abutment means, and latching means movable longitudinally and laterally with respect to said abutment means.

2. A latch comprising abutment means, and latching means adapted to be projected and retracted independently of said abutment means, said latching means moving said abutment means laterally thereof when the latching means is projected.

3. A latch comprising abutment means, and latching means movable longitudinally with respect to said abutment means, said abutment means and latching means movable laterally of each other.

4. A latch comprising abutment means, and latching means movable longitudinally with respect to said abutment means, said latching means formed to provide means for moving said latching means and said abutment means laterally of each other.

5. A latch comprising a casing, abutment means projecting therefrom, and latching means movable longitudinally and laterally with respect to said abutment means.

6. A latch comprising a casing, abutment means projecting therefrom, and latching means adapted to be projected and retracted independently of said abutment means, said latching means moving said abutment means laterally thereof when the latching means is projected.

7. A latch comprising a casing, abutment

means projecting therefrom, and latching means movable longitudinally with respect to said abutment means, said abutment means and latching means movable laterally of each other.

8. A latch comprising a casing, abutment means projecting therefrom, and latching means movable longitudinally with respect to said abutment means, said latching means formed to provide means for moving said latching means and said abutment means laterally of each other.

9. A latch comprising a casing, an abutment member permanently projecting from said casing, and a latching member adapted to be projected and retracted, projection of the latch member causing separation of the abutment and latch members.

10. A latch comprising a part held against substantially all longitudinal movement but free to move laterally, and a part free to move longitudinally and laterally, one of said parts engaging the other part to move both parts laterally.

11. A latch comprising a casing, a member permanently projecting from said casing, a member normally projecting from said casing adapted to be retracted into said casing, relative longitudinal movement of said members causing relative lateral movement of said members.

12. A latch comprising a casing, two members projecting from said casing and normally forced apart, longitudinal movement of one of said members relative to the other allowing said members to move toward each other.

13. A latch comprising a casing, latching means normally projecting from said casing, and means permanently projecting from said casing adapted to clamp said latching means against lateral movement when the latching means is projected.

14. A latch comprising a casing, latching means normally projecting from said casing, and abutment means permanently projecting from said casing, longitudinal movement of said latching means causing lateral movement of said abutment means and latching means.

15. A latch comprising a casing, latching means adapted to be projected and retracted longitudinally, and abutment means permanently projecting from said casing and movable laterally of said latching means.

16. The combination, with keeper means, of normally projecting latching means, and permanently projecting abutment means, said latching and abutment means movable laterally within the keeper means to wedge said latching and abutment means against movement in the keeper means.

17. The combination, with keeper means, of normally projecting latching means, said latching means movable longitudinally to

- engage within the keeper means, and permanently projecting abutment means adapted to engage within the keeper means, said latching means provided with means to 5 wedge the latching and abutment means apart and thereby clamp the latching and abutment means against lateral movement in the keeper means.
18. The combination, with keeper means, 10 of normally projecting latching means longitudinally retracted and then projected to engage within the keeper means, and permanently projecting abutment means adapted to engage within the keeper means, said 15 latching and abutment means movable laterally relatively to each other to clamp said latching and abutment means against lateral movement in the keeper means.
19. The combination, with keeper means, 20 of normally projecting latching means, provided with a rounded end, adapted to be longitudinally projected and retracted, said latching means being retracted when the rounded end of said latching means strikes 25 said keeper means and then projected within the keeper means, and permanently projecting abutment means engaging within the keeper means and cooperating with the latching means to hold the same against rattling within the keeper means.
20. The combination, with keeper means, of abutment means adapted to engage said keeper means, and latching means movable longitudinally and laterally of said abutment means. 35
21. A latch comprising longitudinally extending abutment means, and latching means movable longitudinally and laterally of said abutment means.
22. A latch comprising a casing, abutment means secured against longitudinal movement in said casing and projecting therefrom, and latching means provided with means engaging said abutment means to 40 force the abutment and latching means away from each other.
23. A latch comprising a casing, an abutment member supported against longitudinal movement by said casing and projecting 45 therefrom, and a latch member adapted to be longitudinally projected and retracted, said latch member provided with means adapted to engage said abutment member when the latch member is projected to spread said members apart.
24. A latch comprising a casing, an abutment member, provided with an inclined portion, projecting from said casing, and a latch member adapted to be longitudinally 50 projected and retracted, said latch member provided with an inclined portion adapted to engage said inclined portion of said abutment member when the latch member is projected to spread said members apart.
25. A latch comprising an abutment plate 55 held against longitudinal movement but free to move laterally, and a longitudinally and laterally movable bolt adapted to engage said abutment and move it laterally.
26. A latch comprising a casing, abutment 60 means projecting therefrom, latching means movable longitudinally and laterally with respect to said abutment means, means normally projecting said latching means, and means for retracting said latching means. 70
27. A keeper comprising a flat plate having a beveled portion and provided with a reentrant opening leading from one edge of the keeper, the interior portion of said opening being enlarged. 75
28. A keeper comprising a flat plate having a bent portion and a reentrant opening having a constricted mouth leading from the bent edge of the keeper. 80
29. The combination, with a keeper provided with a beveled portion and a recess, of abutment means adapted to enter the recess in said keeper, and normally projecting latching means adapted to strike the beveled portion of said keeper, said latching means being retracted by contact with said keeper and then projected into said recess. 85
30. The combination, with a keeper provided with a reentrant recess leading from one edge, of permanently projecting abutment means adapted to enter said recess without retraction, and normally projecting latching means of a size too large to enter the mouth of said recess, but small enough to enter the reentrant portion of said recess, said latching means adapted to be retracted by contact with said keeper and then projected into the reentrant portion, projection of said latching means causing lateral movement of the abutment means and latching 90 means within the keeper. 100
31. A latch comprising abutment means, latching means, means normally projecting said latching means and means for retracting said latching means, said latching means provided with means engaging said abutment means when the latching means is projected to force said abutment means against said retracting means and hold the same against rattling. 110
32. A latch comprising a casing, a channel-shaped bolt provided with a rounded end normally projecting from said casing, said bolt provided with an inclined portion intermediate its ends, and an abutment member provided with an inclined portion intermediate its ends and projecting from said casing, the inclined portions of said bolt and abutment member engaging each other when the bolt is projected to force the bolt and abutment member apart. 115
33. A latch comprising a casing, a channel-shaped bolt having a web portion and depending flanges, said bolt provided with a rounded end portion normally projected 120
- 125
- 130

from said casing, said bolt provided with an inclined portion and a projecting lug or tongue intermediate its ends, an abutment member mounted between the flanges of said bolt and permanently projecting from said casing, said abutment member provided with a longitudinal slot or recess and an inclined portion, the inclined portions of said bolt and abutment member engaging each other

when the bolt is projected to spread the bolt ¹⁰ and abutment member apart, and a spring supported in the longitudinal slot or recess of the abutment member engaging the tongue on said bolt and tending to project said bolt from said casing. ¹⁵

In testimony whereof I hereunto affix my signature.

FRANCIS M. VANDERVOORT.
